(57) **CLAIM**

The ornamental design for a lamp housing crown, as shown and described.

DESCRIPTION

FIG. 1 is a right side elevational view of the lamp housing crown in accordance with the design, illustrated in the environment of a lamp, the left side, front side, and rear side being an identical image thereto; and,

FIG. 2 is a top plan view of the lamp housing crown in accordance with the design.

The bottom surfaces and interior walls of the lamp housing crown being flat and unadorned.

The broken lines show the environment in which the article is used and are not considered part of the design claimed.
